UNITED STATES PATENT OFFICE.

VERNON E. BAKER, OF ELYRIA, OHIO.

EMBOSSING DEVICE.

1,402,708.

Specification of Letters Patent. Patented Jan. 3, 1922.

Application filed August 20, 1920. Serial No. 404,938.

To all whom it may concern:

Be it known that I, VERNON E. BAKER, a citizen of the United States, and a resident of the city of Elyria, in the county of Lorain and State of Ohio, have invented a new and useful Improvement in Embossing Devices, of which the following is a full, clear, and exact description.

My invention relates to improvements in embossing devices and it consists in the combinations, constructions and arrangements, herein described and claimed.

An object of my invention is to provide an embossing device that embosses a thin strip of metal during part of its operation and automatically feeds another portion of the strip to be embossed during another part of its operation.

A further object of my invention is to provide a device of the type described that embosses and cuts off a portion of a strip of metal during part of its operation and automatically feeds another portion of the strip to be likewise embossed and cut during another part of its operation.

A further object of my invention is to provide a device of the type described that is simple in construction, efficient in operation, and thoroughly practical commercially.

Other objects and advantages will appear in the specification and the novel features of the invention will be particularly pointed out in the appended claims.

My invention is illustrated in the accompanying drawings, forming part of this application in which—

Figure 1 is a side elevation of the device,

Fig. 2 is a side elevation of the device partly in section,

Fig. 3 is a section on the line 3—3 of Fig. 2,

Fig. 4 is an enlarged portion of the device,

Fig. 5 is an enlarged portion of the device shown in section.

In carrying out my invention I provide a base 1 which is secured to a table or the like by screws 2. A support 3 having a disk-shaped head 4, is integral with the base 1. From the center of the support 3 and extending to the middle of the disk-shaped head 4, is a slot 5 which is adapted to receive a handle 6 pivotally mounted upon a pin 7, that is carried by the disk-shaped head 4 (see Fig. 2).

A horizontal bore 8 extends transversely through the disk-shaped head 4. On each side of the head 9 of the handle 6 are slid-

ably disposed in the bore 8, two disks 10 and 11 which have their outer faces flush with the sides of the disk-shaped head 4 (see Fig. 3). Each of the disks 10 and 11 has a recess on its inner surface which extends in from the periphery as designated at 17' and 18'. Adjacent the outer faces of the two disks 10 and 11 are another pair of disks 12 and 13 that are bigger in diameter than the diameter of the bore 8, and thus bear against the sides of the disk-shaped head 4. The pin 7, which pivotally carries the handle 6, extends through the aligned centrally located bores in the disks 12, 10, 11, and 13, and has a threaded opening extending inwardly a short way from each end in which two screws 14 and 15 are disposed. It will thus be seen that there can be no lateral movement of the moving parts when they are rotated by the handle 6.

Depending from the disk-shaped head 4 is a cylindrical shaped member 16 which has extending inwardly from the bottom a vertical bore 17 (see Fig. 2). Connecting the bore 17 with the bore 8 is a bore 18 which is much larger in diameter than the bore 17, thus forming a shoulder 19 at the junction of the two bores 17 and 18.

A plunger 20 having a diameter which is the same as the diameter of the bore 17 is slidably disposed in the two bores 17 and 18. A compression spring 21 encircles the plunger 20 and is disposed in the bore 18 abutting against the shoulder 19 and a cap 22 which is secured to the top of the plunger 20. The cap 22 carrying with it the plunger 20 is always kept in engagement with a cam surface 23 of the head 9 by the compression spring 21. It will thus be seen that a movement of the handle 6 will raise or lower the plunger 20.

Secured to the bottom of the plunger 20 in any suitable manner is a die carrying member 24. Another die carrying member 25 integral with the base 1 is positioned directly beneath the die carrying member 24. A plurality of male dies 26 are held in place by a set-screw 27 in the member 24 while a set-screw 29 holds a plurality of female dies 28 in position in the member 25. With this construction it is obvious that the dies can easily be changed and thus new printing matter obtained from the same machine.

The member 24 has on its forward underside a cutting edge 30 which is adapted to register with a groove 31 that is on the top of the member 25 (see Fig. 2).

A reel 32 comprising two spaced apart discs 33 is mounted on a pair of arms 34 which are integral with the base 1. The two arms 34 have projecting lugs 35 positioned 5 between the base 1 and the reel 32 which pivotally carry a pair of horizontally disposed contacting rollers 36 and 37. Carried by the roller 37 is a ratchet toothed gear 38 which engages ratchet teeth on a rod 39 pivoted on the rotatable disc 13. The ratchet teeth on the rod 39 engage and rotate the ratchet toothed gear 38 only when the handle 6 is swung up, which movement carries the rod 39 in a downward direction. A thin 10 pliable metal strip 40 is wound around the reel 32 and its free end is frictionally held between the rollers 36 and 37.

From the foregoing description of the various parts of the device the operation 20 thereof may be readily understood. On the upstroke of the handle 6, which is caused by the compression spring 21 forcing the plunger 20 against the cam surface 23 of the head 9, the disk 13 that pivotally carries the 25 rod 39 rotates, and forces the rod 39 down. This movement causes the ratchet teeth in the rod 39 to engage the ratchet toothed gear 38 and to rotate the rollers 36 and 37 a sufficient number of turns to cause a part of the 30 pliable metal strip 40 to be fed between the die carrying members 24 and 25. The handle 6 is then manually forced down against the tension of the spring 21 and brings the two die carrying members 24 and 25 together 35 which causes the metal 40 to be pressed into the various characters produced by the registering of the dies and also cuts the metal strip 40 at the cutting edge 30. This same movement causes the rod 39 to move up with- 40 out engaging the ratchet toothed gear 38 so as to turn it. After the metal has been embossed in the manner described, the first movement again takes place which feeds another section of the metal 40 between the die 45 carrying members 24 and 25, and permits the removement of the piece that has already been embossed and cut.

I claim:

1. An embossing device comprising a base, 50 stationary dies carried thereby, a reciprocating plunger, movable dies carried by said plunger, a handle for operating said plunger, a circular plate rigidly connected to said handle, a rod provided with ratchet teeth pivotally mounted to said plate between the center and the rim thereof, a ratchet toothed gear adapted to be engaged by teeth of said rod when the latter is moved in one direction, means actuated by said 55 ratchet gear for feeding a flexible strip of metal between said dies.

2. An embossing device comprising a base, 60 stationary dies carried thereby, a reciprocating plunger, movable dies carried by said plunger, yielding means tending to hold said

plunger with movable dies away from said stationary dies, a handle for operating said plunger, a circular plate rigidly connected to said handle, a rod provided with ratchet teeth pivotally mounted to said plate between the center and the rim thereof, a ratchet toothed gear adapted to be engaged by teeth of said rod when the latter is moved in one direction, means actuated by said ratchet gear for feeding a flexible strip of metal between said dies. 70

3. An embossing device comprising a base, stationary dies carried thereby, a vertical reciprocating plunger mounted above said stationary dies, movable dies carried by said plunger, a handle for actuating said plunger, yielding means for lifting said plunger with movable dies away from said stationary dies when said handle is raised, a circular plate rigidly connected to said handle, a rod provided with ratchet teeth and pivotally mounted to said plate between the center and the rim thereof, a ratchet toothed gear adapted to be engaged by teeth of said rod when the latter is moved in one direction, means actuated by said ratchet gear for feeding a strip of flexible metal between said dies. 80

4. An embossing device comprising a base, stationary dies carried thereby, a vertical reciprocating plunger mounted above said stationary dies, movable dies carried by said plunger, a handle for actuating said plunger, a compression spring mounted so as to lift said plunger with movable dies away from said stationary dies when said handle is raised, a circular plate rigidly connected to said handle, a rod provided with ratchet teeth and pivotally mounted to said plate between the center and the rim thereof, a ratchet toothed gear adapted to be engaged by teeth of said rod when the latter is moved in one direction, contacting rollers actuated by said ratchet gear for feeding a strip of flexible metal between said dies. 90

5. An embossing device comprising a base, 110 stationary dies fixed to said base, a reciprocating plunger vertically mounted over said stationary dies, movable dies carried by said plunger, means for actuating said plunger, said means comprising a handle having pivotally mounted cam-shaped head adapted to engage said plunger, a compression spring for lifting said plunger with said movable dies away from said stationary dies when said handle is raised, a circular plate rigidly 115 and concentrically connected to the shaft of said cam-shaped head, a rod provided with ratchet teeth and pivotally mounted to said plate between the center and the rim thereof, a ratchet toothed gear adapted to be engaged by teeth of said rod when the latter is moved in one direction, contacting rollers actuated by said ratchet gear for feeding a strip of flexible metal between said dies. 120
